UNITED STATES PATENT OFFICE.

CHARLES HAMMER, OF QUEENS, NEW YORK, ASSIGNOR, BY DIRECT AND MESNE ASSIGNMENTS, TO AMERICAN METAL CAP CO., OF BROOKLYN, NEW YORK.

THREADED-JAR CLOSURE.

1,267,866.

Specification of Letters Patent.

Patented May 28, 1918.

Application filed April 25, 1917. Serial No. 164,355.

To all whom it may concern:

Be it known that I, CHARLES HAMMER, a citizen of the United States, residing at Queens, in the county of Queens and State 5 of New York, have invented certain new and useful Improvements in Threaded-Jar Closures, of which the following is a specification.

This invention relates to bottle closures 10 of the kind made from a strip of metal bent to the form of a cylinder or tube and having a disk secured to one end to close the same; which is provided with a helical corrugation to form a screw thread, to permit 15 the closure to be screwed on a threaded bottle top.

The object of this invention is to provide 20 an improved form of lap for the cylindrical member, whereby the raw edge of the end portion of the blank is concealed, and the lapping portions held in proper position, without the interlocking seam that is usually 25 provided with such construction. Such interlocking seam will form four lapping thicknesses and cause considerable of a bulge 30 that tends to interfere with the corrugated portions, and also provides ridges or channels tending to receive and hold material with which the bottle is filled.

35 A further object of the invention, is to provide integral means in the lapping portions where the screw thread or corrugation is located, that will serve to interlock these portions together, and prevent lateral displacement.

In the accompanying drawing showing 40 embodiments of my invention, Figure 1 shows the blank for the cylindrical part. Fig. 2 shows the middle longitudinal section through the blank with the end portions doubled back on the blank. Fig. 3 shows the completed cap. Fig. 4 is a transverse section on the line 4—4 of Fig. 3. Fig. 5 is a partial transverse section enlarged 45 through the corrugation. Fig. 6 shows the blank of a modification. Fig. 7 is a longitudinal section of the latter. Fig. 8 is a partial vertical section enlarged at the lower end showing the lap joint. Fig. 9 is a partial view showing a modification of the corrugation.

As shown in the drawing I provide a blank 50 in the form of a strip 10 of substantially longitudinal form. The end portions are doubled back on the blank to lie flat against

the same as shown at 11 and 12 in Fig. 2. This blank is bent to the form of a cylinder as indicated in Fig. 4, and the doubled ends are caused to lap a sufficient distance so that each doubled portion extends beyond the other, to bring the edges 13 and 14 into contact, as shown. This will cause the inner face of the outer doubled portion 13 to lie against the other end portion beyond the doubled portion; and will also cause the outer face of the doubled portion 12 to lie against the inner wall of the other doubled portion beyond the bent portion. One end of the cylinder or tube is closed by a disk 15 that is suitably secured to the longitudinal edge of the blank, that is preferably effected by the usual interlocking joint. This will be facilitated by providing notches 16, 17, 18 and 19, so that the doubled portions 12 and 13 will not be included in the portion that interlocks with the disk 15; and the lower or open end of the cylinder will not include the lapping portions.

Suitable interlocking means are provided at the lower open end, in the present instance the lower margin is doubled back outwardly as shown at 20. This doubled portion includes the lapping portion below the doubled portions 12 and 13, as indicated in the section of Fig. 8. This will serve to assist in holding the lapping portions together, as the contiguous raw edges of the doubled portions are brought together and will prevent lateral displacement tending to spread the cylinder. But it will be seen that these edges 13 and 14 are merely brought together in contact and do not lap or interlock as is usual with such construction.

At the lower portion of the cylindrical part the body is given a helical corrugation to provide a screw thread, as indicated at 21. This is done by suitable dies so that the cap can be secured on a screw threaded bottle.

Means are further provided for interlocking the lapping portions at the screw thread 21 that are integral with the metal at such portions. This is done by means of indentations or lugs 22 formed by pressing outwardly the metal by suitable dies. It will be seen from the section shown in Fig. 5 that the lugs on the inner lapping portion extend into the lugs of the outer lapping portion, serving to prevent lateral displace-

ment of the lapping portions. In Fig. 3 these indentations are shown as located only at the middle or highest portion of each thread, but they may extend throughout the 5 threads transversely thereto as indicated in Fig. 9.

In Figs. 6 and 7 is shown a modified form 10 of blank, in which the strip 23 has two projecting portions 24 and 25, in one end, while the other end is provided with the notches 26 and 27. The projections 24 and 25 are doubled back on the blank, and also the portion 28 between the said notches, as indicated in Fig. 7. Otherwise, the formation 15 of the closure is the same as that shown in Figs. 3 and 4.

Having thus described my invention, what I claim is:—

1. A closure cap comprising a body portion 20 formed of a metal strip bent into the proximate form of a cylinder with the strip end portions lapping, the inner edge being doubled back on itself outwardly, and the outer lapping edge of the strip being doubled back on itself inwardly, with the edges of the two bent ends in contact without lapping, the outer face of the inner doubled portion lying against the inner wall of the outer lapping end beyond its doubled portion, and the inner face of the outer doubled 30 portion lying against the outer wall of the inner lapping portion beyond the doubled portion, an end member closing one end of the cylinder and secured thereto, and means 35 for securing the lapping portions at the open end of the closure.

2. A closure cap comprising a body portion 40 formed of a metal strip bent into the proximate form of a cylinder with the strip end portions lapping, the inner edge being doubled back on itself outwardly, and the outer lapping edge of the strip being doubled back on itself inwardly, with the edges of the two bent ends in contact without lapping, the outer face of the inner doubled portion lying against the inner wall of the outer lapping end beyond its doubled portion, and the inner face of the outer doubled portion lying against the outer wall of the inner lapping portion beyond the doubled 45 portion, an end member closing one end of the cylinder and secured thereto, and means for securing the lapping portions at the open end of the closure, the body being provided 50 with a helical corrugation at the lower end portion that includes said lapping portions.

3. A closure cap comprising a body portion 60 formed of a metal strip bent into the proximate form of a cylinder with the strip end portions lapping, the inner edge being doubled back on itself outwardly, and the outer lapping edge of the strip being doubled back on itself inwardly, with the edges of the two bent ends in contact without lapping, the outer face of the inner doubled portion ly-

ing against the inner wall of the outer lapping end beyond its doubled portion, and the inner face of the outer doubled portion lying against the outer wall of the inner lapping portion beyond the doubled portion, 70 the body having the lower margin bent back on itself which includes the lapping portions.

4. A closure cap comprising a body portion 75 formed of a metal strip bent into the proximate form of a cylinder with the strip end portions lapping, the inner edge being doubled back on itself outwardly, and the outer lapping edge of the strip being doubled back on itself inwardly, with the edges of 80 the two bent ends in contact without lapping, the outer face of the inner doubled portion lying against the inner wall of the outer lapping end beyond its doubled portion, and the inner face of the outer doubled 85 portion lying against the outer wall of the inner lapping portion beyond the doubled portion, the body having the lower margin bent back on itself which includes the lapping portions but not the lapping portions 90 that are doubled back.

5. A closure cap comprising a body portion 95 formed of a metal strip bent into the proximate form of a cylinder with the strip end portions lapping, the inner edge being doubled back on itself outwardly, and the outer lapping edge of the strip being doubled back on itself inwardly, with the edges of 100 the two bent ends in contact without lapping, the outer face of the inner doubled portion lying against the inner wall of the outer lapping end beyond its doubled portion, and the inner face of the outer doubled 105 portion lying against the outer wall of the inner lapping portion beyond the doubled portion, an end member closing one end of the cylinder secured thereto, and means for 110 securing the lapping portions at the open end curing the lapping portions at the open end of the closure, the body being provided with a helical corrugation at the lower end portion that includes said lapping portions, the lapping corrugated portions being provided with indentations that interlock to prevent lateral displacement of the lapping portions. 115

6. A closure cap comprising a body portion 120 formed of a metal strip bent into the proximate form of a cylinder with the strip end portions lapping, the inner edge being doubled back on itself outwardly, and the outer lapping edge of the strip being doubled back on itself inwardly, with the edges of 125 the two bent ends in contact without lapping, the outer face of the inner doubled portion lying against the inner wall of the outer lapping end beyond its doubled portion, and the inner face of the outer doubled portion lying against the outer wall of the inner lapping portion beyond the doubled portion, an end member closing one end of 130

the cylinder secured thereto, and means for securing the lapping portions at the open end of the closure, the body being provided with a helical corrugation at the lower end 5 portion that includes said lapping portions, the corrugations at the lapping portions being provided with longitudinally extending ribs in the form of outwardly projecting indentations that interlock to prevent lateral 10 displacement.

7. A closure cap comprising a body por-

tion formed of a metal strip bent into the proximate form of a cylinder with the strip end portions lapping, the body being provided with a helical corrugation at the lower 15 end portion that includes said lapping portions, the corrugations at the lapping portions being provided with longitudinally extending ribs in the form of outwardly projecting indentations that interlock to prevent lateral 20 displacement.

CHARLES HAMMER.
